The schedule referred to in this Letters Patent and making part of the same.

To whom it may concern:

Be it known that I, James Boyle, of West Newton, in the County of Middlesex and Commonwealth of Massachusetts, have invented or produced a new and original Design for an impression by printing on Fabrics known as Floor Oil Cloths, and I do hereby declare that the accompanying Pattern of this date Marked "No. one" and having my signature attested by N. The colors and the adjustment of them may in the use of the design be the same as in said Pattern or be varied at pleasure.

This design of whatever size, in whatever colors in kind or number or in whatever contrasts or blending of colors or of light and shade is the thing I claim as new and as my invention and desire to secure by the Letters Patent of the United States to my assignees agreeably to my assignment & Petition of this 9th day of June 1859.

Witnesses.
